UNITED STATES PATENT OFFICE.

MABEL LUKENS IRWIN, OF PHILADELPHIA, PENNSYLVANIA.

STOCKING-SUPPORTER.

1,150,120.

Specification of Letters Patent. Patented Aug. 17, 1915.

Application filed February 25, 1910. Serial No. 545,907.

To all whom it may concern:

Be it known that I, MABEL LUKENS IRWIN, a citizen of the United States, residing in Philadelphia, Pennsylvania, have invented certain Improvements in Stocking-Supporters, of which the following is a specification.

My invention relates to stocking supporters; and the object of my invention is to provide frictional supporting means for the stocking, avoiding the contact or use of catches, clasps or other forms of fastening members directly with the stocking, but providing a device to embrace the knee that will properly sustain the stocking and at the same time afford means for the attachment of straps or bands connected to and depending from the corset. The frictional supporting means which I have provided preclude all danger of tearing the tops of the stocking, at the same time firmly retaining the stocking in place and affording proper connection with the corset.

These and other features of my invention will be fully pointed out hereinafter, reference being had to the accompanying drawings, in which:

Figure 1, is a perspective view showing my improved stocking supporter in place upon the leg of the wearer; Fig. 2, is a view of the supporter in place, showing the knee bent; Fig. 3, is a perspective view of my improved stocking supporter detached from the person; Fig. 4, is a view illustrating a modified form of one of the elements employed in connection with my improved structure, and Fig. 5, is a sectional view showing the means of attaching the straps or bands connected to and depending from the corset.

The structure forming the subject of my invention comprises a broad band of material, indicated at 1, and designed to embrace the leg of the wearer above the knee, being preferably fastened by suitable means as, for instance, a strap 2 and buckle 3, and overlying the stocking 4 which is usually brought to a point some distance above the knee. Below the knee a band 5, somewhat narrower in width than the band 1, is provided to embrace the leg, and this band may be elastic; being fastened together by a suitable buckle or retaining device 6. The upper band 1 is of friction material and may be wholly of such material, or it may have

a friction strip carried thereby, or a portion that is elastic. In any instance, however, it is preferable that the marginal portions be non-elastic so that no undue constriction of the muscles, veins and arteries can take place in the use of the structure; it being simply fastened by the strap and buckle, or other means, snugly against the leg of the wearer.

Connecting the two bands, which are disposed above and below the knee in the manner shown, are elastic members 7 which may be secured to the upper band and pass through eyes 8 of slotted plates 9 carried by the band 5 at the sides of the leg; such arrangement permitting the elastic members to slip when the knee is bent.

As shown in the drawings, the single looped connections 7 pass loosely through the eyes of the plates 9 or 9^a so as to yield readily and change position with the change of position or movement of the wearer; such plates being also adjustable on the band 5.

The parts of the structure may be connected by sewing, by means of fastener members of any desired character, or in any other suitable manner.

The upper band 1 affords means for the attachment of straps 10 connected to and depending from the corset; such straps having the combined function of holding down the corset and of holding up the stocking, and in order to make their connection with the band 1 entirely practicable and easy of accomplishment, the latter is provided with apertures 11 receiving an ordinary form of fastening carried by said straps 10 and usually employed for this purpose, having a button 12 which extends through the aperture and a retaining member 13 on the other side of the band to engage such button. This is a common form of fastening, and has no relation to my invention. The apertures I have provided, however, are preferably bound at their edges with metal, and in practice the most desirable form of making the bound apertures is to provide eyelets therefor.

In operation, the structure is particularly valuable for its frictional engagement with the stocking, avoiding all danger of tearing holes therein and at the same time affording ample anchoring or connecting means for attachment to the straps or bands connected to and depending from the corset.

The band below the knee should be relatively snug in order that upward pull due to movements of the upper portion of the body confined by the corset will not tend to force such band over the knee.

In Figs. 1, 2 and 3, I have shown one form of plate 9 for connection with the lower encircling band 5, having a single slot 7 for the passage of the connection 7 between the upper and lower bands 1 and 5. In the structure shown in Fig. 4, however, I have provided a plate 9^a having a series of slots 8^a in case it should become desirable to adjust the connecting means 7 with respect to said encircling bands.

I claim:

1. In a stocking supporter, the combination of a non-elastic band encircling the leg above the knee, adjustable securing means for the same, an independent and separate elastic band encircling the leg below the knee, adjustable securing means for the same, elastic connections between said bands disposed at opposite sides of the leg whereby the front and rear knee inclosing portions of the structure are left free and unobstructed, and guides for said elastic connections carried by one of the leg-encircling bands whereby said elastic connections are free to slip between the leg-encircling bands and automatically adjust themselves when the knee is bent.

2. In a stocking supporter, the combination of a non-elastic band adapted to encircle the leg above the knee, adjustable securing means for the same, an independent and separate elastic band adapted to encircle the leg below the knee, elastic straps disposed at the sides of the leg between said bands, said straps being permanently secured to the non-elastic band, means carried by the elastic band for adjusting the position of the elastic side connections with respect thereto; the front and rear knee inclosing portions of the structure being left free and unobstructed, and guides for said elastic connections carried by one of the leg-encircling bands whereby said elastic connections are free to slip between the leg-

encircling bands and automatically adjust themselves when the knee is bent.

3. In a stocking supporter, the combination of a non-elastic band encircling the leg above the knee, an independent and separate continuous elastic band encircling the leg below the knee, independent adjustable means for securing said respective bands in place, elastic connections extending between said bands at the opposite sides of the same whereby the front and rear knee inclosing portions of the structure are left free and unobstructed, guides for said elastic connections carried by one of the leg-encircling bands whereby said elastic connections are free to slip between the leg-encircling bands and automatically adjust themselves when the knee is bent, said guides being adjustable on said elastic leg-encircling band, and said non-elastic band having provision for the engagement of straps depending from a corset.

4. In a garter or stocking supporter, the combination of a pair of independent adjustable elements for completely encircling the leg at separate points above and below the knee, one of said elements being elastic, elastic connecting means for said elements disposed at the opposite sides of the leg whereby the front and rear knee inclosing portions of the structure are left free and unobstructed, and guides for said elastic connections carried by one of the leg-encircling bands whereby said elastic connections are free to slip between the leg-encircling bands and automatically adjust themselves when the knee is bent; said elastic connecting means being permanently secured to one of said leg-encircling elements and adjustable with respect to its connection with the other leg encircling element.

In testimony whereof I have signed my name to this specification, in the presence of two subscribing witnesses.

MABEL LUKENS IRWIN.
